UNITED STATES PATENT OFFICE

167,859

FLAG

Robert S. Ryan, Montgomery, Ala., assignor to Chamber of Commerce of Montgomery, Montgomery, Ala.

Application April 9, 1952, Serial No. 19,259

Term of patent 14 years

(Cl. D29—2)

To all whom it may concern:

Be it known that I, Robert S. Ryan, a citizen of the United States, residing at Montgomery, in the county of Montgomery, and State of Alabama, have invented a new, original, and ornamental Design for a Flag, of which the following is a specification, reference being had to the accompanying drawing, forming part thereof.

The single figure is a side elevational view of a flag showing my new design.

The flag is of a conventional thickness.

The drawing is lined for color.

I claim:

The ornamental design for a flag, as shown and described.

ROBERT S. RYAN.
